START AND STOP MECHANISM FOR TALKING-MACHINES.

1,357,560.

Specification of Letters Patent.

Patented Nov. 2, 1920.

Application filed July 15, 1915. Serial No. 40,060.

To all whom it may concern:

Be it known that I, FRANK C. HINCKLEY, a citizen of the United States of America, and a resident of Bridgeport, Connecticut, have invented a new and useful Improvement in Start and Stop Mechanism for Talking-Machines, which invention is fully set forth in the following specification.

This invention relates to start and stop mechanism, and more particularly to mechanism adapted to automatically stop, and also preferably to automatically start, a talking machine. It is designed especially for use in connection with that class of talking machines in which a tone-arm or other tubular sound-conductor, together with the reproducer, is advanced across the face of a disk record in the act of reproducing said record. With said devices it is desirable that the machine be automatically started when the operator places the reproducer and tone-arm in position to commence reproduction and automatically stopped when, for any reason, the reproducer and tone-arm cease their advance movement across the face of the record. The present invention has for an object the provision of a start and stop mechanism that will accomplish the above ends and, as respects certain features, it is an improvement on the device described and claimed in patent to Woods & Hinckley, 1,264,588, of Apr. 30, 1918.

Other objects of the invention are to provide an improved start and stop mechanism of simplified, cheaper and more efficient construction, and an improved start-and-stop mechanism and mounting therefor.

The invention will be better understood by reference to the accompanying drawings, illustrating one embodiment of the inventive idea, and wherein,

Figure 1 is a plan view, the sound-record and the motor-board being broken away to show the improved start-and-stop mechanism;

Fig. 2 is a side elevation, partly in section, corresponding to Fig. 1;

Fig. 3 is a section on the line 3—3 of Fig. 2, looking in the direction of the arrows;

Fig. 4 is a perspective view of the two frictional washers;

Fig. 5 is a sectional view on the line 5—5 of Fig. 2, looking in the direction of the arrows;

Fig. 6 is a perspective view of the differential elements and the connections between one of the same and the tone-arm; 55

Fig. 7 is a disassembled perspective view of one end of the plunger mechanism and the parts carried thereby; 60

Fig. 8 is a horizontal sectional view through the end of the plunger;

Fig. 9 is a vertical elevation showing the mounting of the differential elements;

Fig. 10 is a vertical section, partly in elevation and on an enlarged scale, showing one end of the plunger and the mechanism carried thereby in a locked position; 65

Fig. 11 is a plan view showing the device associated with a spring motor; and 70

Fig. 12 is a detail perspective.

In the embodiment of the invention shown on the drawings, wherein like reference numerals indicate like parts, 15 is a motor-board which preferably is formed in two parts and hinged together, at 16, for a purpose which will be hereinafter more fully stated. Projecting through an eyelet 17 in said motor-board is a hollow stationary member 18 provided with an annular flange 19 that extends through said motor-board. A tone-arm 20 is mounted on said stationary member 18, and secured to said tone-arm is a sleeve 21 which participates in the movement thereof. This sleeve is provided with a pair of slots that are engaged by a pair of corresponding lugs 22 carried by a second sleeve 23, preferably formed integrally with a toothed sector 24. This sector moves with the tone-arm and operates in a casting 25, which casting is fixedly secured to the flange 19 in any suitable manner, as by a pair of screws 26 (Figs. 1 and 2). This casting is provided with a bottom and two side walls, and the top of said casting is closed by a cover 27 which is preferably secured in place by screws 28 and 29. 80 85 90 95

The toothed sector 24 meshes with a pinion 30 (see Figs. 3 and 6) fast on vertical shaft 31 having bearings in the cover 27 and the bottom of casting 25. On the lower end of said shaft 31 is keyed a bevel gear 32 which meshes with a corresponding bevel gear 33 mounted on a stub shaft having bearings in casting 25. This bevel gear 33 has preferably formed integrally therewith a cam 34, which rotates, through the connections described, when the tone-arm 20 is 100 105

moved to the position for starting the reproduction of a sound-record, and this cam operates suitable mechanism to effect the starting of the motor, whether an electric motor 5 as illustrated in Fig. 1, or a spring motor as illustrated in Fig. 11.

When an electric motor is used, there is preferably employed a plunger 35 carrying a contact piece 36 (Figs. 2 and 6) which is 10 adapted to close an electric circuit through terminals 37 and 38 contained in box 39, said terminals 37 and 38 being connected to any suitable source of current through conductors carried by the cable 40. The plunger 15 35 projects through a sleeve 41 carried by a part of the casting 25, and a spiral spring 42 encircles said plunger, one end of said spring engaging the sleeve 41 and the other end of said spring abutting against a head 20 43 provided on said plunger. This head 43 carries a downwardly depending lug 44 which engages in a slot 45 in said sleeve, the function of this lug being to keep the head 43 from turning. The head is freely movable 25 inward, the extent of movement being determined by the terminals 37 and 38.

The head 43 is recessed at 46 (Fig. 7) and carries a pin 47 that projects through a tumbler 48 provided with a flattened face 30 49 which normally engages the rear face 50 of said recess 46. This tumbler 48 is provided with a pair of jaws between which is secured an anti-frictional roller 51 that is engaged by the cam 34. A spring 52 acts to 35 normally hold the parts in the position shown in Fig. 8. This mounting of the tumbler 48 permits the cam 34 to readily return to its original position when the tone-arm is moved back to its starting position.

40 In the upper face of the plunger head 43 there is provided a transverse slot 53 provided with inclined walls 54 and 55 (Fig. 10) and a latch 56, pivoted at 57 (Fig. 5) in the casting 25, is adapted to engage in said slot to hold the plunger in its innermost position, at which time the electric circuit is completed and the motor running. The latch 56 is held in the slot 53 by the engagement therewith of a pin 58 provided at its 50 other end with an opening through which passes a stud or shaft 59 having bearings in standards 60 (Fig. 9) in the casting 25. This pin 58 carries a bevel pinion 62 which is loosely revolvable thereon, said pinion being held in place by a collar 63. Pinion 62 meshes continually with a pair of bevel gears 64 and 65, both of which are loosely mounted on shaft 59. Said gears 64 and 65 are of the same size, and are adapted to rotate in 55 opposite directions, the gear 64 being rotated by the movement of the tone-arm 20 and the gear 65 being rotated from the motor.

The connections between the gear 64 and the tone-arm are best shown in Figs. 2, 3, 4, 65 6 and 9. A suitable friction-drive is inter-

posed between said gear 64 and the tone-arm and, in the form shown, a pair of friction disks 66 and 67 are mounted on shaft 31, said disks being provided with lugs 68 that engage a key-way in the shaft 31, so that said disks always rotate with said shaft. Loosely mounted between said disks on the shaft 31 is a gear wheel 69. This friction-drive, among other things, prevents speeded manual movement of the tone-arm 20 from being attended by injurious results and, generally, makes the device "fool-proof." The friction connection also allows the tone-arm to be returned to its initial position.

One end of a spring 70 abuts disk 67 and the other end of said spring engages a collar 71 fixed on the shaft 31, whereby the desired driving engagement is had between the friction disks and the gear 69. Said gear 69 meshes with a pinion 72 keyed or otherwise secured to a shaft 73 having bearings in the top 27 and the bottom of the casting 25. Keyed to said shaft 73 is a worm wheel 74 that meshes with a worm 75 (Figs. 6 and 9), preferably integrally formed on the shank 90 of the bevel gear 64 which, as heretofore stated, is loosely mounted on the stud 59. The worm wheel 74 and the worm 75 constitute what is known as an "irreversible gear," and the connection constitutes a "one-way" 95 drive; that is to say, worm wheel 74 can drive worm 75, but worm 75 cannot drive worm wheel 74. This insures prompt operation of the stop mechanism upon the stopping of the tone-arm and bevel gear 64. If worm 75 100 could drive worm wheel 74, the motor would not be stopped until all lost motion or looseness in the gearing between gear 64 and the tone-arm had been taken up.

The power connections between the bevel 105 gears 64 and 65 and their respective driving elements are so proportioned that the gear 64 always tends to move faster than the gear 65 which is driven from the motor, and this tendency of said gear 64 to move faster than 110 its companion acts to hold the pin 58 to its seat and to keep the plunger 35 locked. The tendency of gear 64 to be driven faster than gear 65 is compensated for or taken up by the friction-drive between the tone-arm and 115 said gear 64.

The connections between the motor 76 and bevel gear 65 are best shown in Figs. 1, 5 and 9. Referring to Fig. 1, a worm 76' driven by the motor meshes with a worm 120 wheel 77' mounted on shaft 77 on which is also mounted a worm 78 which meshes with a worm wheel 78' mounted on a stub shaft 79, to one end of which is secured, by a universal joint 80, a flexible shaft 81. The 125 other end of this shaft is provided with a universal joint 82 which carries a plug 83 that projects into a union 84 and is held therein by frictional engagement. This union also receives one end of a stub shaft 130

85 which has bearings in ears 86 and 87 on the casting 25 (Fig. 1). Mounted on said stub shaft 85 is a pinion 88 that meshes with a gear 89 (Fig. 5) carried by a stud 90 mounted in the ear 86. Preferably formed integrally with gear 89 is a pinion 91 that meshes with a gear 92, which latter is preferably formed integrally with the bevel gear 65 which, as heretofore stated, is mounted 10 loosely on the stud or shaft 59.

The motor 76 is secured to the motor-plate 15 by any suitable means as screws 92', four of which are shown in Fig. 11. It will be observed that all of the mechanism heretofore described is located to the right of the hinge 16, and by means of this construction the motor and all of its associated parts, including the mounting of the tone-arm and the start-and-stop mechanism, may be 15 readily exposed to view by turning up the part 15 of the motor-board in the direction of the arrow 93 shown in Fig. 2. When it is desired to inspect the normally inclosed parts, it is only necessary to turn thumb 20 screws 94 shown in full lines in Fig. 2 and in dotted lines in Fig. 11, and then to elevate the motor-board 15. The motor-board 15, which is preferably of metal, sometimes bows or springs, but the provision of the 25 flexible shaft 81 and universal joints 80 and 82 prevents this action from having any injurious effect on the mechanism, as by binding or otherwise.

The device has heretofore been described 30 in connection with an electric motor. The invention may, however, be equally well employed in connection with a spring motor, and such a construction is shown in Figs. 11 and 12. When the device is associated 35 with a spring motor, the contact member 36 is removed from the end of plunger 35, and one end of a link 95 is suitably secured to said plunger. The other end of said link is secured to one end of an arm 96, the other end of which is fastened to a vertical shaft 97. This shaft 97 has rigidly secured thereto a second arm 98 to which is fastened, in any suitable manner, the carrier 99 for the friction pads 100 which are moved 40 into and out of engagement with the friction disk 101 carried by the governor shaft 102. When the plunger 35 is moved inwardly, the parts are operated to remove the pads 100 from engagement with the disk 101, and 45 when the plunger 35 is moved in the opposite direction, or toward the right, by spring 42, the pads are moved into braking engagement with the disk 101.

The operation of the device is as follows: 50 When it is desired to effect reproduction of a record, the tone-arm is moved into engagement with the record groove and, by reason of the connections heretofore described, the disk 34 which carries the cam

projection 34' rotates as said tone-arm is so 55 moved, this rotation causing engagement between the cam face 103 and the roller 51, thereby moving the plunger 35 toward the left in the direction of the arrow in Fig. 6. At the same time, through gear 69, pinion 70 72, worm wheel 74 and worm 75, the bevel gear 64 is rotated. The motor 76 has not yet started and, accordingly, the rotation of bevel gear 64 effects a rotation of pinion 62, thus moving said pinion and its associated 75 pin 58 bodily in a clockwise direction (Fig. 5) until the beveled lower end of said pin 58 engages the upper surface of the latch 56 which, at this time, has dropped into the groove 53 provided in the head 43 of the 80 plunger 35. The movements of the pin 58, latch 56 and plunger 35 are so timed that, when the end of the incline 103 of the cam projection 34' is reached, the latch will drop into the slot 53 where it will be held by the 85 pin 58, and it is at this time that the motor circuit is completed and, through the connections heretofore described, the bevel gear 65 commences to rotate in a direction opposite to that of bevel gear 64. The rotation 90 of gears 64 and 65 in opposite directions acts to effect a rotation of the bevel pinion 62 without, however, effecting any displacement of this pinion with respect to either gear 64 or 65, the tendency of gear 64 to 95 rotate faster than gear 65 acting to hold the pin 58 against the left-hand end of slot 58' (Fig. 5). So long then as reproduction is being effected, the pinion 62 simply rotates on its axis. When, however the tone-arm 100 reaches the end of the record, or stops for any other reason, the bevel gear 64 will cease rotating, but the bevel gear 65, being driven from the motor, will continue to rotate. Thereupon the pinion 62 (see Fig. 5) will be 105 displaced in an anti-clockwise direction to a position indicated by the dotted line in Fig. 5, whereupon the spring 42 will cause the plunger 35 to move toward the right, the latch 56 being cammed out of the slot 53, 110 and the motor circuit will be opened and the motor stopped. If, now, the tone-arm is moved back across the record to the starting position, the disk 34 and the cam projection 34' will be rotated in the opposite direction, 115 and the face 104 of the cam projection will engage the roller 51. By reason of the mounting of the tumbler 48, this engagement will effect rocking of the tumbler on the pin 47 against the action of the spring 120 52, whereby the cam projection 34' clears the tumbler without moving the plunger 43 inwardly.

While, for the purpose of illustration, one expression of the inventive idea is herein 125 shown and described in detail, it is to be understood that the invention is not limited to this construction, but that the inventive idea

is susceptible of various mechanical expressions within the limits of the appended claims.

What is claimed is:—

- 5 1. In combination, a motor, a traveling element, a movable member connected to and moving therewith, a second movable member driven from the motor, stop mechanism operable upon the stopping of one of 10 said members, and means preventing movement of said first-mentioned movable member except from the traveling element.
- 15 2. In combination, a motor, a traveling element, a movable member connected to and moving therewith, a second movable member driven from the motor, stop mechanism operable upon the stopping of one of said members, and an irreversible gear, connection 20 between the traveling element and said first-mentioned movable member preventing the transmission of power from the latter to the former.
- 25 3. In combination, a motor, a traveling element, a movable member connected to and moving therewith, a second movable member driven from the motor, stop mechanism operable upon the stopping of one of said members, and a worm wheel driven by said traveling element and meshing with a worm 30 connected to said first-mentioned movable member, whereby an irreversible gear connection is provided.
- 35 4. In combination, a motor, a traveling element, a rotatable member connected to and rotated by the movement of said traveling element, a second rotatable member driven from the motor, a third rotatable member engaged by the other two members, stop mechanism operatively related to said third 40 rotatable member, and means preventing rotation of said first-mentioned rotatable member except from the traveling element.
- 45 5. In combination, a motor, a traveling element, a rotatable member connected to and rotated by the movement of said traveling element, a second rotatable member driven from the motor, a third rotatable member engaged by the other two members, stop mechanism operatively related to said third 50 rotatable member, and an irreversible gear connection between the traveling element and said first-mentioned movable member preventing the transmission of power from the latter to the former.
- 55 6. In combination, a motor, a traveling element, a rotatable member connected to and rotated by the movement of said traveling element, a second rotatable member driven from the motor, a third rotatable 60 member engaged by the other two members, stop mechanism operatively related to said third rotatable member, and a worm wheel driven by said traveling element and meshing with a worm connected to said first-mentioned bevel gear, whereby an irreversible gear connection is formed.

tioned movable member, whereby an irreversible gear connection is provided.

7. In combination, a motor, a traveling element, a rotatable member connected to and rotated by the movement of said traveling element, a second rotatable member driven from the motor in the opposite direction, a third rotatable member engaged by the other two members, stop mechanism operatively related to said third rotatable member, and means preventing rotation of said first-mentioned rotatable member except from the traveling element.

8. In combination, a motor, a traveling element, a gear rotated by the movement of said traveling element, a second gear rotated from said motor in the opposite direction to that of said first gear, a third gear meshing with said other two gears and rotated thereby, stop mechanism operatively related to said third gear, and means preventing rotation of said first-mentioned gear except from the traveling element.

9. In combination, a motor, a traveling element, a bevel gear rotated by the movement of said traveling element, a second bevel gear rotated from said motor in the opposite direction to that of said first bevel gear, a third bevel gear meshing with said other two bevel gears and rotated thereby, stop mechanism operatively related to said third bevel gear, and means preventing rotation of said first-mentioned bevel gear except from the traveling element.

10. In combination, a motor, a traveling element, a bevel gear rotated by the movement of said traveling element, a second bevel gear rotated from said motor in the opposite direction to that of said first bevel gear, a third bevel gear meshing with said other two bevel gears and rotated thereby, stop mechanism operatively related to said third bevel gear, and an irreversible gear connection between said traveling element and said first-mentioned bevel gear preventing transmission of power from said gear to said element.

11. In combination, a motor, a traveling element, a bevel gear rotated by the movement of said traveling element, a second bevel gear rotated from said motor in the opposite direction to that of said first bevel gear, and a third bevel gear meshing with said other two bevel gears and rotated thereby, stop mechanism operatively related to said third bevel gear, and a worm wheel driven by said traveling element and meshing with a worm connected to said first-mentioned bevel gear, whereby an irreversible gear connection is formed.

12. In combination, a motor, a traveling element, a rotatable member connected to and rotated by the movement of said traveling element, a second rotatable member driven

from the motor, a third rotatable member engaged by the other two members, stop mechanism operatively related to said third rotatable member, and a yieldable friction-
5 drive interposed between said traveling element and said first-mentioned rotatable member.

13. In combination, a motor, a traveling element, a gear rotated by the movement of
10 said traveling element, a second gear rotated from said motor in the opposite direction to that of said first gear, a third gear meshing with said other two gears and rotated thereby, stop mechanism operatively related to
15 said third gear, and a yieldable friction-drive interposed between said traveling element and said first-mentioned gear.

14. In combination, a motor, a traveling element, a bevel gear rotated by the movement
20 of said traveling element, a second bevel gear rotated from said motor in the opposite direction to that of said first bevel gear, a third bevel gear meshing with said other two bevel gears and rotated thereby, stop mechanism operatively related to said
25 third bevel gear, and a yieldable friction-drive interposed between said traveling element and said first-mentioned bevel gear.

15. In combination, a motor, stop mechanism therefor comprising a movable element, a tumbler carried thereby, a traveling element, a rotatable cam adapted to engage
30 said tumbler to displace said movable element, and connections between said cam and
35 traveling element.

16. In combination, a motor, start mechanism therefor comprising a movable element, a traveling element, a rotary cam adapted to engage said movable element to
40 displace the same, and gear connections between said cam and traveling element.

17. In combination, a motor, start mechanism therefor comprising a movable element, a pivoted tumbler carried thereby, a traveling element, a cam adapted to engage
45 said tumbler to displace said movable element, and connections between said traveling element and cam for rotating the latter in both directions.

50 18. In combination, a traveling element, a member yieldably driven thereby, a motor, a second member driven thereby, a third member in continuous engagement with said

first and second members, a stop device, and a detent for said stop device released by
55 said third member upon the stopping of said traveling element.

19. In combination, a motor, a traveling element, a member moved by said traveling element, a second member moved by said
60 motor, a device in continuous engagement with said members, a flexible driving connection between said motor and said second member, and stop mechanism automatically rendered operative by said device by the
65 stopping of one of said members.

20. In combination, a motor, a gear driven thereby, a flexible driving connection intermediate said gear and motor, a traveling element, a member moved thereby, stop
70 mechanism, and means in continuous engagement with said gear and member and automatically effecting the actuation of said stop mechanism upon the stopping of said member.

75 21. In combination, a motor, a member rotated thereby, a flexible driving connection intermediate said motor and member, a traveling element, a second member rotated thereby, a third member in continuous engagement with said first and second members, and stop mechanism operatively related to said third member.

22. In combination, a motor, a traveling element, members respectively rotated by
80 said motor and traveling element, a pivot engaged by said first named members, stop mechanism operatively related to said pivoted member, and a yieldable friction-drive interposed between said pivoted member and
90 the traveling element.

23. In combination, a motor, start mechanism therefor comprising a movable element, a traveling element, a cam adapted to engage said movable element to displace the
95 same, and connections between said cam and traveling element including a frictional drive.

In testimony whereof I have signed this specification in the presence of two sub-
scribing witnesses.

FRANK C. HINCKLEY.
